UNITED STATES PATENT OFFICE.

CHARLES L. KLINE, OF CHICAGO, ILLINOIS.

PROTRACTOR.

SPECIFICATION forming part of Letters Patent No. 724,018, dated March 31, 1903.

Application filed October 21, 1902. Serial No. 128,147. (No model.)

To all whom it may concern:

Be it known that I, CHARLES L. KLINE, a citizen of the United States, residing at Chicago, in the county of Cook and State of Illinois, have invented certain new and useful improvements in Protractors; and I do declare the following to be a full, clear, and exact description of the invention, such as will enable others skilled in the art to which it appertains to make and use the same.

This invention relates to protractors.

The object is to provide an instrument of this character which is simple of construction, readily adjustable, comparatively inexpensive of manufacture, and designed to afford superior facilities for angle-work.

With this and other objects in view the invention consists of certain novel features of construction, combination, and arrangement 20 of parts, as will be more fully described, and particularly pointed out in the appended claims.

In the accompanying drawings, Figure 1 is a plan view of the obverse side of a protractor embodying my invention. Fig. 2 is an edge view thereof. Fig. 3 is a section on the line 3 3 of Fig. 1. Fig. 4 is a section on the line 4 4 of Fig. 1. Fig. 5 is an enlarged detail section on the line 5 5 of Fig. 1. Fig. 6 is a 30 plan view showing the application of the auxiliary blade, a portion of the upper face of the protractor being broken away to show the pivot and form of the adjacent portion of the main blade.

Referring now more particularly to the drawings, 1 represents the protractor-blade, provided with a scribing edge 2, a right-angular flange 3 at one end projecting beyond the scribing edge and an ear 4 also extending beyond the scribing edge at a point adjacent to said flange. The blade is further provided with a slot 5 at a point below the ear 4 and with a rib 6 in longitudinal alignment with the scribing edge 2 and having an 45 overhanging flanged end 7. This rib bears the fixed indicator line or point 8.

9 denotes the protractor-segment, pivoted at the center of its straight side by a pin or screw 10 to the ear 4 and consisting of obverse and reverse segmental plates 11 and 12, held united and spaced apart by rivets 13,

forming an interposed recess to receive the blade 1, on the opposite sides of which the plates are thereby positioned, as clearly shown in Fig. 2. The upper or obverse plate 11 is 55 provided with scale-graduations to coöperate with the indicator line or point 8. It will be observed that by pivoting the segment at a certain distance out from the scribing edge 2 the scribing edge when the segment is set 6c at an acute angle will be continuous from the pivot to the extreme end; also, that by forming the protractor-segment with obverse and reverse sides disposed on opposite sides of the blade the operator by first using one 65 side of the instrument and then turning it over and using the other side may obtain perfectly-correct reverse angles.

The lower half of the plate 11 of the protractor is formed adjacent to its straight edge 70 with a slot 14 and has connected thereto at one end a spring-detent 15, the free end of which is provided with a head 16, forming a finger-piece and a catch to engage the slot 5. This head is adapted to move in the slot 5 75 and is tapered or wedge-shaped at its base to frictionally engage the walls of said slot 5. Normally the resilience of the detent maintains the head out of engagement with slot 15; but when the segment is adjusted to a position at right angles to the blade the slot 14 comes into register with slot 5, and the operator by pressing down on the head 16 may force the wedge-shaped portion of the head through slot 14 and into slot 5, the frictional 80 engagement of the wedge-shaped portion with the walls of slot 5 serving to hold the head secured therein and the segment fixed against movement. A slight upward pull on the upper portion of the head will, however, disengage the same from the slot 5 and the spring action of the detent will retract the head to its normal position and release the segment from locking engagement with the blade 1. By the provision of this detent the operator 85 may obtain a quick adjustment of the segment to a position at right angles without inspecting the graduations, as the slot 5 and detent form a perfect register for such adjustment, and the detent enables the segment to 90 be held against movement in this position until the clamping-screw (hereinafter described) 95

is tightened to securely clamp the segment against casual movement while the instrument is in use.

The curved edges of the segment-plates 11 and 12 are formed with flanges 17, which are engaged by the flanged edges 19 of two clamping-plates 20 20', disposed on opposite sides of the flange 3, and the flange on the plate 11 is also engaged by the flanged end 7 of the rib 6, whereby a guide is formed for the said curved edges of the plates, and the edge of the plate 11 is prevented from springing out of registering alinement with the rib. The clamping-plates are provided with dowel-pins 21 to fit within an opening 22 in the flange 3 and also with an opening to receive a clamping-screw 23, which also passes through the flange and by means of which the plates 20 20' may be drawn together to clamp the flanges 20 and hold the segment against movement or forced apart and disengaged from the flanges to release the segment. This construction provides a clamp which is effective in action, may be quickly applied and released, and when applied holds the segment firmly against movement at any desired angle.

In order to enable an extreme obtuse angle to be obtained, I provide an auxiliary blade 24, having a forked end 25 to enter between the plates 11 and 12 and straddle the pivot 10, whereby the blade may be held in position for use in the manner shown in Fig. 6.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. A protractor comprising a blade, a protractor-segment pivoted thereto and consisting of spaced connected plates disposed on opposite sides of the blade, clamps disposed on opposite sides of the blade and adapted to engage the curved edges of the plates, and

means for adjusting said clamps, substantially as described.

2. A protractor comprising a blade having a flange and a pivoting projection extending beyond its working edge, a protractor-segment consisting of a pair of plates disposed on opposite sides of the blades, means for spacing and connecting the plates, means pivotally connecting the plates to said pivoting projection, clamps disposed on opposite sides of said flange to bear upon the curved edges of the plates, and means for adjusting said clamps, substantially as described.

3. A protractor comprising a blade having a flange and a pivoting projection extending beyond its working edge, a protractor-segment consisting of a pair of plates disposed on opposite sides of the blades, means for spacing and connecting the plates, means pivotally connecting the plates to said pivoting projection, clamps disposed on opposite sides of said flange to bear upon the curved edges of the plates, and means for adjusting said clamps, and a rib upon the blade adjacent said flange and bearing an indicator-point and having a flanged edge engaging the edge of one of the protractor-plates, substantially as described.

4. A protractor comprising a blade having a flange and a pivoting projection extending beyond its working edge, a protractor-segment consisting of a pair of plates disposed on opposite sides of the blades, and each having a flanged curved edge, means for spacing and connecting the plates, means pivotally connecting the plates to said pivoting projection, clamps disposed on opposite sides of said flange to bear upon the flanged curved edges of the plates, means for adjusting said clamps, and a rib upon the blade adjacent said flange and having a flanged edge engaging one of the flanged edges of the plates, substantially as described.

In testimony whereof I have hereunto set my hand in presence of two subscribing witnesses.

CHARLES L. KLINE.
